(57) CLAIM

The ornamental design for a gas tank cover substantially as shown and described.

DESCRIPTION

FIG. 1 is a top isometric view of a gas tank cover.
FIG. 2 is a bottom isometric view of the gas tank cover of FIG. 1.

FIG. 3 is a front elevation view of the gas tank cover of FIG. 1.

FIG. 4 is a rear elevation view of the gas tank cover of FIG. 1.

FIG. 5 is a left side elevation view of the gas tank cover of FIG. 1.

FIG. 6 is a right side elevation view of the gas tank cover of FIG. 1.

FIG. 7 is a top plan view of the gas tank cover of FIG. 1; and, FIG. 8 is a bottom plan view of the gas tank cover of FIG. 1.

The broken lines in the drawings illustrate portions of the gas tank cover that form no part of the claimed design.

1 Claim, 8 Drawing Sheets
